UNITED STATES PATENT OFFICE.

JOHN C. DAVIS, OF SENECA FALLS, NEW YORK.

DESIGN FOR A PUMP-BASE.

SPECIFICATION forming part of Design No. 25,070, dated January 21, 1896.

Application filed August 19, 1895. Serial No. 559,854. Term of patent 3¹ years.

To all whom it may concern:

Be it known that I, JOHN C. DAVIS, a citizen of the United States, residing at Seneca Falls, county of Seneca, State of New York, have invented a certain new and original Design for a Pump-Base; and I declare the following to be a full, clear, and exact description of the design, such as will enable others skilled in the art to which it pertains to make and use the same, reference being had to the accompanying drawing, which forms a part of this specification.

My invention relates to the design of the base portion of the pump—that is, that portion which rests upon the floor and supports the pump-cylinder.

The invention has heretofore been applied to that class of air-pumps wherein the pump is steadied by means of the foot inserted in the base, although it is obvious that it need

not necessarily be limited to this class of pumps, but might be used on any other pump.

The figure in the drawing is a perspective view of my pump-base.

In carrying out the invention D represents the base. It is a broad flat piece or portion d, which near the ends is narrowed by curved lines d², said narrowed ends terminating in the upwardly-projecting inwardly-curved arms d³, said arms being tapered, as at d⁴.

What I claim is—

The design for a pump base substantially as herein shown and described.

In testimony whereof I sign this specification in the presence of two witnesses.

JOHN C. DAVIS.

Witnesses:

EDWARD L. BOWELL,
THOMAS W. POLLARD.
